UNITED STATES PATENT OFFICE.

JAMES A. McLAUGHLIN, OF JESUP, GEORGIA.

HAY-CURING RACK.

1,301,145.

Specification of Letters Patent. Patented Apr. 22, 1919.

Application filed July 3, 1918. Serial No. 243,158.

To all whom it may concern:

Be it known that I, JAMES A. McLAUGHLIN, a citizen of the United States, residing at Jesup, in the county of Wayne and State 5 of Georgia, have invented certain new and useful Improvements in Hay-Curing Racks; and I do declare the following to be a full, clear, and exact description of the invention, such as will enable others skilled in the art 10 to which it appertains to make and use the same.

My invention has for its object to provide an extremely simple and inexpensive, yet a highly efficient and in every way desirable 15 rack for curing hay in the field and then hauling the same to the baling press or to the mow as occasion may require, and with this end in view, a further object is to provide a rack which may be compactly stored 20 when not in use.

With the foregoing in view, the invention resides in the novel features of construction and unique combinations of parts to be hereinafter fully described and claimed, the descriptive matter being supplemented by the 25 accompanying drawings which form a part of this specification and in which:

Figure 1 is a side elevation of the invention;

30 Fig. 2 is an end elevation;

Fig. 3 is a substantially central vertical transverse section on the plane of the line 3—3 of Fig. 1; and

Fig. 4 is an end elevation of the device 35 folded for storing.

Briefly speaking, the improved rack comprises a pair of side frames F hinged together at their upper ends at H, transverse bars B, open guides G on the frames F 40 movably receiving the ends of the bars B, skids S upon which the side frames are mounted, and shoes S' applicable to the front ends of these skids when they are in use.

55 Each frame F includes a pair of inclined end bars 1 secured at their lower ends to the skids S, and a plurality of longitudinal bars 2 extending between and beyond the end bars and secured to the latter. The hinges H connect the upper ends of the bars 1 of the two frames as shown. The transverse bars B project beyond the frames F and rest on the bars 2, being preferably notched at 3 to receive said last named bars, 55 whereby to prevent spreading of the two frames. Certain of the bars B abut the

inner sides of the end bars 1, while others are located between the ends of the bars 2, vertical strips 4 being provided to prevent the bars B from shifting longitudinally of the bars 2. The strips 4 extend across and are secured to the bars 2, and certain of these strips are employed for holding the bars B against the end bars 1, while the other strips 4 are located on opposite 60 sides of the center bars B. To prevent end-wise tilting of the transverse bars when more hay is piled on one end thereof than the other, longitudinal strips 5 are secured to the end bars 1 and to the strips 4, said 65 longitudinal strips overlying the ends of the bars B as shown, sufficient upward movement of said ends being permitted, however, to allow the notches 3 to be disengaged from the bars 2 when the device is to be folded. 70 Each frame F is preferably braced as seen at 75 6 or in any other preferred manner.

The skids S are secured to the lower ends of the end bars 1 and have their ends beveled upwardly, and in order to provide for 80 the easy drawing of the entire rack along even the roughest ground, without allowing the front ends of the skids to snub against stones, roots and the like, the shoes S' are provided, the front ends of said shoes turning 85 upwardly a considerable distance as shown at 7. The body portions of the shoes S' are hollow and are so shaped as to be easily forced over the front ends of the skids, by the teamster, when the hay rack 90 and the cocks of hay thereon are to be moved. When this is to be done, a transverse draft bar 8 having a forwardly extending hitch 9 is provided, said bar resting on the skids S in rear of the front end bars 1 and having shoulders 9 abutting the inner edges of 95 said bars to prevent possible inward movement thereof.

In use, the racks are set up in the field and the hay cocks are formed thereon, the 100 openwork construction of the racks serving to effectually air-cure the hay in a few days. A team is then hitched to the racks and they are thus drawn to the baling press or to the place at which the hay is to be stored 105 away in a mow or the like. When the use of the rack is no longer needed, the transverse bars B are disengaged from the guides G and the two frames F may then be folded toward each other for compact storing. It 110 may here be pointed out that the several guides referred to are formed by component

parts of the frames F. In the present showing, certain of said guides are formed by the coöperation of the end bars 1, the longitudinal bars 2, certain of the vertical strips 4, and the longitudinal strips 5, while the central guides are formed solely by the bars 2, the longitudinal strips 5, and the remaining strips 4. It will be obvious that this is an extremely simple and inexpensive 10 construction, yet that such construction is highly efficient and in every way desirable.

In the present application I have illustrated but one embodiment of the hay rack, but it is to be understood that within the 15 scope of the invention as claimed, numerous minor changes may well be made in this form, and that the device may also be embodied in other forms.

I claim:

- 20 1. A hay curing rack comprising a pair of upwardly converging side frames hinged together at their upper ends, transverse bars extending between and beyond said side frames, and open guides on said side frames 25 through which said transverse bars extend removably.
2. A hay curing rack comprising a pair of upwardly converging side frames hinged together at their upper ends, and transverse 30 bars extending between and beyond said side frames, certain component parts of said frames forming open guides through which said transverse bars extend removably.
3. A hay curing rack comprising a pair 35 of upwardly converging side frames hinged together at their upper ends, and transverse bars extending between and beyond said side frames, each frame having vertical and longitudinal bar members spaced apart to form 40 open guides through which said transverse bars extend.
4. A hay curing rack comprising a pair of upwardly converging side frames each consisting of substantially vertical end bars, 45 longitudinal bars extending between and beyond and secured to said end bars, fixed strips extending parallel with said end bars and across said longitudinal bars in proximity to the former, hinges connecting the 50 two frames and secured to the upper ends of said end bars, and transverse bars extending between and beyond said frames,

said transverse bars resting removably on said longitudinal bars between said end bars and said strips.

5. A hay curing rack comprising a pair of upwardly converging side frames each consisting of substantially vertical end bars, longitudinal bars extending between and beyond and secured to said end bars, fixed 60 strips extending parallel with said end bars and across said longitudinal bars in proximity to the former, hinges connecting the two frames and secured to the upper ends of said end bars, transverse bars extending 65 between and beyond said frames, said transverse bars resting removably on said longitudinal bars between said end bars and said strips, and longitudinal strips secured to said end bars and overlying said transverse 70 bars to prevent longitudinal tilting thereof.

6. A hay curing rack comprising a pair of side frames converging upwardly and hinged together at their upper ends, each frame including longitudinal bars, transverse bars extending between and beyond said side frames and resting on said longitudinal bars between the ends of the latter, and parallel strips crossing and secured to said longitudinal bars on opposite sides of 80 said transverse bars.

7. A structure as specified in claim 5, together with additional transverse bars extending between and beyond said frames and resting on said longitudinal bars between the ends of the latter, and parallel strips secured to and crossing said longitudinal bars, said parallel strips being positioned on opposite sides of said additional 85 transverse bars.

8. In combination with a hay rack having skids, a pair of shoes for application to the front ends of said skids when the rack is to be drawn from one place to another, said shoes being hollow to receive the front ends 95 of the skids and having their front ends turned upwardly to a greater extent than said skids.

In testimony whereof I have hereunto set my hand.

JAMES A. McLAUGHLIN.
